UNITED STATES PATENT OFFICE.

HARRIET LYONS REDMOND, OF BOSTON, MASSACHUSETTS, ASSIGNOR TO THE
WILLIAM CARTER COMPANY, OF NEEDHAM HEIGHTS, MASSACHUSETTS, A
CORPORATION OF MASSACHUSETTS.

UNDERGARMENT.

1,405,000.

Specification of Letters Patent. Patented Jan. 31, 1922.

Application filed February 2, 1921, Serial No. 441,904.

To all whom it may concern:

Be it known that I, HARRIET LYONS REDMOND, a citizen of the United States, and a resident of Boston, in the county of Suffolk,

5 State of Massachusetts, have invented an Improvement in Undergarments, of which the following description, in connection with the accompanying drawings, is a specification, like characters on the drawings representing like parts.

This invention relates to undergarments and particularly to union undergarments having the lower portion of woven material and the upper portion of a more elastic and 15 preferably knitted material.

In order that the principle of the invention may be readily understood, I have disclosed a single embodiment thereof in the accompanying drawings, wherein—

20 Fig. 1 is a front elevation of a union undergarment constructed in accordance with my invention;

Fig. 2 is a rear elevation thereof.

The garment of my invention is an undergarment and is preferably a union garment for ladies' wear having the main portion thereof 1 including the part below the bust, and the legs formed of some suitable woven material. The crotch construction of the 25 garment as indicated at 2 may be of any suitable character, whether closed crotch, open crotch or drop seat. The leg portions 3 may be of any suitable length. Desirably the garment is provided with a seam extending from the crotch portion upwardly to the bust portion, as indicated at 4 in Fig. 1, and a similar seam at 5 extending up the back. Desirably also the lower portions 3 are provided with seams 6 at the inner parts thereof.

40 The upper portion of the garment including at least the bust portion, as indicated at 7 in Fig. 1, and desirably also including the upper portion of the back, as indicated at 8 in Fig. 2, is of a more elastic material and 45 is preferably knitted. In such construction, the wales of the knitted material desirably extend circumferentially or transversely of the garment, thus rendering the same very highly elastic. As indicated in Figs. 1 and

50 2, the upper edge of the bust portion, as indicated at 9, is upwardly rounded so as to give a proper amount of fullness. If desired, the upper edge may be formed as a hem to receive a cord, tape or ribbon 10.

Attached to the upper edge of the knitted portion 7, 8 are shoulder straps or bands 11.

The knitted parts 7, 8 are attached to the upper edge of the woven part of the body 1 in any suitable manner, as by stitching.

The garment thus constructed is relatively 60 inelastic throughout the main portion of the body 1, but is desirably made relatively loose throughout the main portion. The knitted portion 7, 8, is, however, relatively 65 highly elastic, but nevertheless, in contrast with the loose body portion, it constitutes an excellent bust support to the uncorseted woman, and particularly to women in athletics. So far as I am aware, I am the first

70 to provide in a single garment the two features of a clinging but elastic bust support and a loose woven main body portion. The knitted portion or portions may be formed by plain knitting upon a series of needles,

75 as by supplying a single thread to all the needles, or it may be formed by so-called warp knitting, wherein a plurality of threads are employed, each thread being introduced to but a few needles. The warp knitted fabric has been found highly advantageous 80

for this particular use by me, since it does not unravel except to a very limited extent upon breaking of a thread, because of the peculiar way in which it is knitted.

85 If desired and within the scope of my invention the knitted portion may be confined to the front of the body; that is, to the bust portion, but as herein shown, the knitted part extends entirely about the body.

Having thus described one illustrative embodiment of my invention, I desire it to be understood that although specific terms are employed, they are used in a generic and descriptive sense and not for purposes of limitation, the scope of the invention being 90 set forth in the following claims:

1. A union garment having the part below the bust formed of woven material and the bust portion and the corresponding part of the back formed of knitted material wherein 100 the wales extend transversely of the garment.

2. A union undergarment for women having the part below the bust formed wholly of woven material and of proportions to fit 105 the figure loosely, the bust portion of the garment being composed of knitted material whereof the wales extend transversely of the

fabric so as to constitute a bust support for the uncorseted body, the upper edge of the garment terminating upon a transverse line below the top of the shoulders, said garment being open at the top and having securing straps passing over the shoulders.

3. A union undergarment for women having the part below the bust formed wholly of woven material and of proportions to fit the figure loosely, the bust portion and the corresponding portion at the back of the garment being composed of knitted material whereof the wales extend transversely of the fabric so as to constitute a bust support

for the uncorseted body, the upper edge of the garment terminating upon a transverse line below the top of the shoulders, said garment being open at the top and having securing straps passing over the shoulders.

4. A union garment having the part below the bust formed of woven material and the bust portion formed of knitted material, wherein the wales extend transversely of the garment.

In testimony whereof I have signed my name to this specification.

HARRIET LYONS REDMOND.
